DISPENSING DEVICE

George R. Beeg, Yonkers, N. Y.

Application December 5, 1933, Serial No. 700,975

4 Claims. (Cl. 91—67.4)

This invention relates to dispensing devices, and more particularly to devices applicable to bottles of mucilage and the like.

Among the principal objects which the present invention has in view are: To provide an improved dispensing device which automatically seals the bottle or the like on which it is attached, and yet provides for adequate flow of mucilage or the like when desired; to prevent clogging by 10 hardening of the mucilage after use; to enable the device to be wiped on the surface in either of two opposite directions and give a flow of mucilage under either condition; to avoid tendency to seal against discharge of the mucilage or the like during the wiping operation; to afford increased flow 15 of mucilage or the like by increased pressure; to enable use of a wide tip to be employed for securing an even spreading of the mucilage or the like; and to obtain other advantages and results 20 as may be brought out in the following description.

Drawing

Figure 1 is a side elevation of a bottle having my invention thereon;

Figures 2 and 3 are sectional views shown as taken on line 2—2 of Figure 1;

Figure 4 is a plan view; and

Figure 5 is a sectional view of a modified construction of cap having a threaded interior.

Description

As seen in the drawing, the reference numeral 10 is a bottle or the like, the upper end of which is mounted a cap 11 as shown in Figures 1 to 3 designed to be sold as a unitary part with the bottle, tightly fitting upon the neck 12 thereof. It is to be understood, however, that if so desired the cap may be made removable for refilling the bottle, or may be made and sold independent of the bottle, in which event it may be threaded as at 13 as shown in Figure 5, or otherwise constructed to be attached to bottles now appearing on the market.

Cap 11 may be of any desired material, the construction shown being one capable of utilizing such materials as hard rubber, "bakelite", and other substances which are not flexible, or if preferred, the cap may be constructed of flexible or semi-flexible material thereby enabling it to be attached to bottle necks of somewhat varying size and shape. As here shown, cap 11 is frustoconical with the base portion thereof cylindrical and annular by virtue of an apron or flange portion 14, this flange portion 14 constituting the neck-engaging part of the cap 11.

Projecting from the outer or smaller end of the cap 11 is a flexible and normally closed neck 15 which is preferably a construction closely resembling a spiral spring, the convolutions of which tightly close one against the other except when spread apart in use as shown in Figure 3. The convolutions of this neck are resilient in order to maintain the normally closed condition above specified and to return said neck to such closed condition after release of any deforming 10 pressure which has separated any of the convolutions. By use of a spiral spring-like neck 15, the end convolutions thereof may readily be embedded within the outer end of cap 11, seating therein as a screw in a threaded socket. 15

The outer end of the neck 15 carries a spreader 16 of hard rubber or other suitable material, the neck preferably having its end convolutions embedded therein, with the spreader effectually closing the outer end of the interior channel formed 20 by the neck 15. Consequently, the only opportunity for the escape of the contents 17 of the bottle 10, for convenience referred to herein as mucilage, is through the gaps or crevices between adjacent convolutions created by deformation or 25 lateral displacement of the neck. Furthermore, the spreader may conveniently be provided with a crosshead 18 transverse to the axis of the neck and of such length, shape, and dimensions and material as found most desirable for spreading the 30 mucilage escaping through the neck. It is preferable to have the crosshead of greater length than the diameter of the neck so as to fully spread all material discharged from the neck.

In use, it will be noted that the normal resiliency 35 and closed condition of the spirally formed neck 15 causes the same to maintain a tight closure for the bottle 10 even with the bottle upside down. When, as in Figure 3, the spreader 16 is pressed against a surface 19, neck 15 is deformed with 40 gaps appearing between convolutions at the side of the neck towards the surface, therefore, contents 17 from the bottle 10 will drip on to the surface. Drawing the bottle along the surface results in crosshead 18 of spreader 16 wiping over 45 the discharged contents. By moving the bottle in a reversed direction, the neck swings and opens at its opposite side, and again the spreader wipes over the contents after discharge. Releasing the pressure immediately closes the neck and no 50 further contents will be discharged.

The natural tendency to press down with greater force when insufficient contents are discharged will be effective in the use of my invention because the additional pressure applied ob- 55

tains greater deflection of the neck 15, increasing the size and number of gaps open between convolutions of the contents 17 to the surface 19 since the part forming the gaps is not in direct contact with the surface. After the device has been in disuse for a period enabling the mucilage to dry, the same pressure to distort the neck 15 for again applying mucilage to a surface necessarily disrupts any adhesion of the dried mucilage between convolutions of the neck and thus free passage of the mucilage is obtained just as readily on subsequent utilization of the device as exists the first time it is used.

I claim:

- 15 1. A dispensing device comprising in combination with a cap and a spreader, a flexible neck outside said device having a plurality of parts normally closed together and adapted to be spread apart by flexing said neck and thereby providing lateral openings exterior of and between the cap and spreader for enabling contents within the neck to be discharged adjacent the exterior of the spreader.
- 20 2. A dispensing device comprising in combination with a cap and a spreader, a flexible neck outside said device having a plurality of spiral convolutions normally closed together and adapted to be spread apart by flexing said neck and thereby providing lateral openings exterior of and between the cap and spreader for enabling contents within the neck to be discharged adjacent the exterior of the spreader.
- 25 30

tween said convolutions adjacent the exterior of the spreader.

3. A dispensing device comprising in combination with a cap and a spreader, a flexible neck outside said device and embedded at its opposite ends in said cap and spreader respectively, said neck having a plurality of spiral convolutions normally closed together and adapted to be spread apart by flexing said neck and thereby providing lateral openings exterior of and between the cap 10 and spreader for enabling contents within the neck to be discharged between said convolutions adjacent the exterior of the spreader.

4. A dispensing device for applying a fluid to work comprising in combination with a bottle having a neck, a cap and a spreader, said cap fitting snugly on the neck of said bottle, a spiral spring having a plurality of convolutions normally tightly closed, one end of said spring adapted to fit within the said cap on the inside of the neck 20 of the bottle for admitting the bottle contents to the exterior of the spring upon inverting the bottle, and the outside end of the spring being adapted to support said spreader whereby on inversion of the bottle downward pressure on the spreader causes the convolutions of the spiral spring to separate and the contents from within the bottle to escape directly therethrough onto the work in proximity to the spreader.
